UNITED STATES PATENT OFFICE.

JAMES K. DOBBS, OF ATLANTA, GEORGIA.

INTERNAL-COMBUSTION ENGINE.

1,115,515.

Specification of Letters Patent. Patented Nov. 3, 1914.

Application filed September 3, 1913. Serial No. 788,038.

To all whom it may concern:

Be it known that I, JAMES K. DOBBS, a citizen of the United States, residing at Atlanta, in the county of Fulton and State of Georgia, have invented certain new and useful Improvements in Internal-Combustion Engines, of which the following is a specification, reference being had to the accompanying drawings.

10 This invention comprehends certain new and useful improvements in internal combustion engines and has for its primary object to provide an internal combustion engine of improved operation.

15 Another object is to provide an internal combustion engine which will be provided with curved slide valve members forming a divided sleeve around the cylinder and water jacket.

20 A further object resides in the provision of an internal combustion engine with transversely curved slide valve members of this character and means for supplying a lubricant to the upper ends of said members during operation of the same.

25 A further object is to generally improve the construction of the cylinder and water jacket and the casing within which said cylinder and water jacket are secured.

30 A still further object resides in the construction of an internal combustion engine of this character in which the cylinder and water jacket are cast separately from the casing and secured in said casing in a novel 35 and improved manner whereby they may be readily removed and replaced should the same be necessary.

35 A still further object is to provide an internal combustion engine of this character 40 with novel and improved mechanism for operating the piston and the slide valve members and provide improved lubricating and water cooling systems for the engine.

45 This invention has for a further object to generally improve and simplify the construction and operation of the various parts of the engine and increase the efficiency and durability thereof and at the same time reduce the cost of the same.

50 With the above and other objects in view, my invention consists in certain novel constructions, combinations, and arrangements of parts to be hereinafter more fully described, claimed, and illustrated in the accompanying drawings in which,

55 Figure 1 is an elevational view of my

complete engine. Fig. 2 is an enlarged fragmentary plan view of one of the cylinder casings, said view showing in section, a portion of said casing and one of the cylinders and valve members within the same. Fig. 3 is a vertical section on the line 3—3, of Fig. 2. Fig. 4 is a similar view on the line 4—4, of Fig. 3. Fig. 5 is a detail vertical sectional view on the line 5—5, of Fig. 2; and Fig. 6 is a detail elevational view of one of the curved slide valve members removed.

Referring more specifically to the drawings in which similar reference characters 70 designate corresponding parts throughout the several views, 1 designates the base and 2 the cylinder casing which is preferably cast in one piece and formed to accommodate two cylinders as will be readily understood by referring to the drawings. The casing 2 is preferably of rectangular form in cross-section and as the cylinder chambers 3 formed therein by the circular walls 4, said circular walls being connected at the 80 center of the casing, as shown at 5. By providing the circular walls 4 in this manner, I have produced substantially triangular oil chambers 6 at the corners of the casing and the larger oil chambers 7 about 85 midway the length of the longitudinal edges of the casing, the portions of the circular walls 4 forming the curved walls of the oil chambers 6 and 7 being provided with transverse slots near their upper ends, through 90 which oil chambers 6 and 7, oil will flow, as will be clearly understood. It will be understood that the oil chambers 6 and 7, may be connected with one another, if desired. 95

Within each chamber 3 is positioned a cylinder 10 formed of inner walls 11 and outer walls 12 to form the water chamber therebetween, the outer wall 12 being provided with a plurality of spaced annular 100 grooves 14 preferably arranged in pairs and adapted to accommodate packing rings 15. The cylinder is provided with diametrically opposite intake and exhaust passages 16 and 17, respectively, extending through the walls 105 11 and 12 and the inner wall 11 is directed inwardly, as shown at 18, near its upper end and then outwardly, as shown at 21. This also increases the size of the upper portion of the water chamber. By forming the upper portion of the cylinder in this manner, 110 I have also reduced the size of the combus-

tion chamber above the intake and exhaust passages 16 and 17, respectively, and I have shown the reduced end wall 49 of the combustion chamber as being provided with 5 three openings 50, within which spark plugs and a petcock (not shown), may be secured. The cylinder is secured in position against the ceiling of the chamber 3 by means of the threaded extensions 22 formed on the 10 upper end of the cylinder 10 and engaged through the ceiling of the chamber 3 and having nuts or the like 23 upon their extended ends. The cylinder 10 is also provided upon its upper end with the water 15 outlet extension 24, which extension is also engaged through the ceiling of the chamber 3, which has connected thereto a water outlet pipe 24 leading to the radiator or to any other suitable point. It will be understood 20 that cool water from a radiator or other suitable point passes by means of the water inlet pipe 25 into the lower end of the water chamber 13, as shown in Fig. 3.

Slidably engaged within the chamber 3 around the outer wall 12 of the cylinder 10 are the inlet and outlet slide valve members 26 and 27, respectively, which are of substantially semi-circular form in cross-section and are provided respectively with the 30 inlet and outlet ports 28 and 29. It will be seen that the slide valve members 26 and 27 form a complete sleeve around the outer wall 12 of the cylinder 10, thereby locating the slide valve members outwardly of the 35 water chamber 13. The slide valve member 27 is provided in its lower portion with the longitudinally extending slot 30 to accommodate the water inlet pipe 25, thereby permitting the slide valve member 27 to operate 40 properly.

Each of the slide valve members 26 and 27 has a pair of depending parallel ears 31 through which is positioned a pivot pin 32 and upon the pivot pin 32 is mounted one 45 end of a pitman rod 33, the opposite end of which is mounted upon the crank portion of a crank shaft 34 having its opposite ends mounted in the bearings 35 in the crank shaft casing 36, said crank shaft having the 50 gear wheel 37 mounted thereon. The gear wheels 37 are engaged and operated by a gear wheel 38 mounted on the main shaft 39. Upon the crank portion of the shaft 39 is mounted one end of the piston rod 55 41, the opposite end of said piston rod being connected with the piston 42 within the cylinder 10 in the usual manner.

It will be seen that by the connection between the main shaft 39 and crank shafts 60 34 and connections between the crank shafts 34 and the slidable valve members 26 and 27, said valve members will be properly operated in opposite directions to bring the intake and exhaust ports 28 and 29 respectively, in-position opposite the inlet and

outlet passages 16 and 17 at the proper time. It will also be understood that the intake and exhaust pipes 43 and 44 are connected with the casing 2 at diametrically opposite points and opposite the intake and exhaust 70 passages 16 and 17, respectively.

The intake pipes 43 for the two cylinders within the casting 1 are connected, as shown at 45, and the exhaust pipes 44 for said cylinders are also connected, as shown at 75 46. Likewise, the two water inlet pipes are connected to the single pipe 47 and the water outlet pipes 24 are connected to a single pipe 48.

It will be evident that during operation of 80 the slide valve members 26 and 27, oil from the large oil chambers 7 will pass through the transverse slots 8 and fall upon the upper curved edges of said slide valve members 26 and 27 and gradually find its way to the 85 crank casing 36, thereby thoroughly lubricating the operative parts of the engine. It will also be seen that owing to the extremely simple and novel construction of 90 the various parts and the manner in which 95 said parts are connected, the engine may be readily assembled or taken apart and will be highly efficient and effective in use as well as positive in operation. It will further be seen that should any of the parts become 95 worn or broken, they may be readily replaced at small cost.

While I have shown the preferred form 100 of my internal combustion engine, it will be understood that minor changes in the 100 details of construction may be made within the scope of the appended claims without departing from the spirit of my invention or sacrificing any of the advantages of the same.

What I claim is:—

1. An engine comprising a cylinder having inner and outer walls to form a water chamber between said walls, curved slide valve members around said cylinder, a casing around the cylinder, a water supply pipe extending through the casing into the water chamber, one of said curved slide valve members being provided with a slot to accommodate the water supply pipe, a water outlet pipe leading through the casing from the water chamber, a piston within the cylinder, means for operating the piston, said casing and cylinder being provided with intake and exhaust ports, said curved slide members being provided with intake and exhaust ports adapted to register with said intake and exhaust ports of the cylinder and casing, and a spark plug carried by said cylinder.

2. An engine comprising a cylinder having inner and outer walls to form a water chamber between said walls, curved slide valve members around said cylinder, a casing around said cylinder outwardly of said

- curved slide valve members, a piston within the cylinder, means for operating the piston, said casing and cylinder being provided with intake and exhaust ports, said curved slide valve members being provided with 5 intake and exhaust ports adapted to register with said intake and exhaust ports of said casing and cylinder, said casing having oil chambers around the cylinder, certain walls 10 of said oil chambers being provided with slots through which oil may find its way to the curved slide valve members, and a spark plug carried by said cylinder.
3. An engine comprising a cylinder having 15 inner and outer walls to form a water chamber between said walls, curved slide valve members around said cylinder, a casing around the cylinder, a water supply pipe extending through the casing into the water chamber, one of said slide valve members being provided with a slot to accommodate the water supply pipe, a water outlet pipe leading through the casing from the water chamber, a piston within the cylinder, means for operating the piston, said casing and cylinder being provided with intake and exhaust ports, said curved slide valve members being provided with intake and exhaust ports adapted to register with 25 said intake and exhaust ports of the cylinder and casing, said casing having oil chambers around the cylinder, certain walls of said oil chambers being provided with slots through which oil may reach the curved slide valve members, and a spark plug carried by said cylinder.
4. An engine comprising a cylinder having 30 inner and outer walls to form a water chamber between said walls, curved slide valve members around said cylinder, a casing around the cylinder outwardly of the curved slide valve members, a water supply pipe extending through the casing and into the water chamber, one of said curved slide 35 valve members being provided with a slot to accommodate the water supply pipe, a water outlet pipe leading through the casing from the water chamber, a piston within the cylinder, means for operating the piston,
- ton, said casing having spaced oil chambers 50 around the cylinder, the inner walls of said oil chambers adjacent their upper ends being provided with slots through which oil may find its way to the upper ends of the curved slide valve members, and a spark 55 plug carried by said cylinder.
5. An engine comprising a one-piece cylinder including spaced inner and outer walls to form a water chamber between said walls, the outer wall being provided 60 with openings near its opposite ends, a water supply pipe secured in one of said openings, a water discharge pipe secured in the other of said openings, a portion of the inner wall being directed inwardly to provide 65 a reduced combustion chamber at one end of the cylinder, a spark plug in said end of the cylinder, the opposite end of the cylinder being open, a piston within the cylinder, means for operating the piston, a casing for 70 said cylinder, said casing having oil chambers formed around the cylinder, slide valve members engaged between the outer wall of the cylinder and the inner walls of the oil chambers, one of said slide valve members 75 being slidably engaged over the water supply pipe, said cylinder having intake and exhaust ports through its spaced walls and through the water chamber, said casing having intake and exhaust ports opposite the first mentioned intake and exhaust ports, said slide valve members being provided with intake and exhaust ports adapted to 80 register respectively with the intake and exhaust ports of the cylinder and casing, and means connected with the last mentioned operating means for operating the slide valve members, said inner walls of the oil chambers being provided with openings 85 whereby oil from said chambers may be deposited upon the slide valve members.
- In testimony whereof I hereunto affix my signature in the presence of two witnesses.
